US00D822488S

(12) **United States Design Patent** (10) Patent No.: **US D822,488 S**
 Staab et al. (45) Date of Patent: ** Jul. 10, 2018

(54) **COSMETIC CAP**

- (71) Applicant: **Mary Kay Inc.**, Addison, TX (US)
- (72) Inventors: **Jenny DeMarco Staab**, Frisco, TX (US); **Lauren Purkhiser**, Addison, TX (US); **Priscilla Ober**, Addison, TX (US)
- (73) Assignee: **Mary Kay Inc.**, Addison, TX (US)
- (**) Term: **15 Years**
- (21) Appl. No.: **29/628,162**
- (22) Filed: **Dec. 1, 2017**

Primary Examiner — Dana L Meyrow*(74) Attorney, Agent, or Firm* — Norton Rose Fulbright
US LLP(57) **CLAIM**

The ornamental design for a cosmetic cap, as shown and described.

DESCRIPTION

FIG. 1 is a top perspective view of a cosmetic cap showing our new design;

FIG. 2 is a front view of the cosmetic cap shown in FIG. 1; FIG. 3 is a back view of the cosmetic cap shown in FIG. 1; FIG. 4 is a right side view of the cosmetic cap shown in FIG. 1;

FIG. 5 is a left side view of the cosmetic cap shown in FIG. 1; and, FIG. 6 is a top view of the cosmetic cap shown in FIG. 1. The dashed lines in FIGS. 1-6 are included for the purpose of illustrating portions of the cosmetic cap that form no part of the claimed design.
